APPARATUS FOR MAKING DOUBLE
WALLED TUBE

Emil Francis Svec, New York, N.Y.; Viera M. Svec, executrix of said Emil F. Svec, deceased, assignor to Flexigrip, Inc., New York, N.Y., a corporation of New York
Original application Dec. 16, 1957, Ser. No. 703,033, now
Patent No. 3,088,495, dated May 7, 1963. Divided
and this application Apr. 30, 1962, Ser. No. 196,025
2 Claims. (Cl. 18—14)

This application is a division of U.S. application Serial No. 703,033, filed December 16, 1957, now Patent No. 3,088,495.

This invention relates to apparatus for making a multi-walled thermoplastic strip. More specifically, this invention relates to apparatus for making a multi-walled thermo-plastic strip including fastener structure disposed along opposite edges of the strip for locking the edges together and forming the strip into a tube.

According to certain important aspects of the present invention, there is provided a thermo-plastic tube type strip having interlocking edges with a multi-wall structure having a plurality of compartments which double walled strip has a number of advantages a few of which are now described. The double wall tube construction provides increased protection for article or articles covered therein against mechanical damage, and against dirt, oil and the like. This double wall strip structure also has high insulating properties. Double walled tubes of the present type also may be utilized to protectively encase a series of electrical wires and the like.

Accordingly, it is an important object of the present invention to provide apparatus for making a thermo-plastic multi-walled strip construction having interlocking engageable edges for folding the strip into a tube.

A further object of the present invention relates to novel apparatus for manufacturing a multi-walled thermo-plastic strip.

Yet another object of the present invention concerns a novel apparatus for manufacturing a multi-walled thermo-plastic strip having peripheral edges adapted for interlocked engagement to form the strip into a tube.

Yet another and still further object of this invention is to provide means for extruding a multi-walled thermo-plastic strip including means for maintaining the walls of the strip separated until they are hardened so they will not collapse upon being discharged from the extruder.

Other and further important objects of this invention will become apparent from the following detailed description and the appended claims, and from the accompanying drawings illustrating a preferred embodiment of this invention, in which like reference numerals refer to like parts and in which:

FIGURE 1 is a fragmentary, partly cross-sectioned extruder device shown extruding a strip, according to the features of the present invention;

FIGURE 2 is an enlarged fragmentary cross-sectional view taken substantially on the broken section line II—II of FIGURE 1, looking in the direction indicated by the arrows;

FIGURE 3 is a fragmentary perspective view of a multi-walled thermo-plastic strip provided with interlocking edges, according to certain features of the present invention; and

FIGURE 4 is an enlarged fragmentary end elevation of the interlocked edges of the double-walled tube shown in FIGURE 3.

The reference numeral 10 in FIGURE 1 indicates generally an extruded double-walled strip and the reference numeral 11 in FIGURE 3 indicates generally the strip 10 folded into tubular form in a manner which will herein-

2

after become apparent. In the form in which the strip 10 would be sold, it may be a flat strip of extended length, capable of being bent transversely into the tube 11, or being wrapped about smaller tubes, cables or the like into the seamed tube-form shown in FIGURE 3.

The strip 10 is preferably a strip of relatively thin, flexible material, suitably formed from a plastic such as vinyl polymer or copolymer, as for instance, polyvinyl chloride, or from polyethylene, or other substantially water- and moisture-proof plastic material having high dielectric strength and suitable strength against being torn or ruptured despite its relative thinness.

According to the present invention, the strip is preferably extruded flat in a manner which will hereinafter be described in detail although it will be appreciated that the tube could be extruded initially in tubular form, with the tube then being severed between the thickened edge portions to permit the tube to be flattened out.

As best shown in FIGURE 4, the thickened edge portions 12 and 13 are identical in cross section but offset in opposite directions from the plane of the strip 10 and are adapted to confront each other when overlapped and formed into a tube. Since the closure strips 12 and 13 are otherwise identical, only one need be described. A closure strip is provided with alternating, adjacent grooves 15, 15a and ribs 16, and 16a that extend continuously along the edge portion 12. Two such grooves 15, 15a and two such ribs 16, 16a are shown, although a greater number of grooves and ribs can be used if desired. The ribs and grooves are complementally formed and the ribs are provided with enlarged head portions 17 and restricted neck portions 18, between which are formed edges 19 that impart to the ribs a hook-like contour. When the closure strips 12 and 13 are matingly inter-engaged, the edges 19 of the ribs 16, 16a are in opposed relationship to resist lateral separation of the edges 12 and 13.

Closure of the tube to form the seam S can be effectuated manually by incrementally pressing together successive portions of the confronting closure elements of the edge portions 12 and 13. While a slider can be used for the purpose, it is preferable to take the slider away, once the closure elements are engaged, since then the seam S will be substantially water- and moisture-tight throughout its extent. Where the article 10 is made of thermo-plastic material, the seam S can be permanently closed by cementing (gluing) the edges strips 12 and 13 together along their contacting surfaces.

According to other important features of the present invention, the strip 10 and the tube 11 are provided with a multi-walled construction which is here illustrated as a double walled form of my invention since additional walls may be readily formed without departing from this invention. The double wall construction includes a first wall 20 which wall has at its opposite ends the closure strips 12 and 13. A second wall 21 is also mounted on the strip 10 and tube 11 whereby link or hinge portions 22—22 are disposed at opposite ends of the wall 21 and extend transversely with respect to the walls 20 and 21 and interconnect these walls generally at the area of the closure strips 12 and 13. This double walled strip construction when utilized as a tube provides increased protection for articles covered therein against mechanical damage, and against dirt, oil and the like. This double wall strip structure also has high insulating properties.

As will be noted from FIGURE 2, the first wall 20 lies in a first plane when the multiple walled strip is lying flat, and the edge closure strips 12 and 13 lie along the edges of the wall 20.

The second wall 21 is substantially parallel to the first wall 20, and the hinge portions 22 support it in a second plane. This structure also makes it more easy to form

the multi-walled unit into a tube. It will be apparent that the circumferences of the two layers must be different, and to accommodate this change when the multi-walled strip is rolled into a tube, the hinge portions 22, 22 will bend, permitting the walls to form a circle without undue stress. This also permits the tube to be rolled in either direction, and in FIGURE 3 the tube is shown rolled with the second wall 21 on the inside of the first wall 20. As will be observed, the tube could be rolled in the other direction with the second wall 21 on the outside. This could easily be accommodated in view of the laterally extending hinge portions 22, 22. Any pulling on the second wall portion 21 in the arrangement shown in FIGURE 3 will not result in a direct tensile stress being placed on the first wall 20, since the laterally extending hinge portions 22, 22 can first bend before direct pull is exerted on the first wall 20. It will be noted that the laterally extending hinge portions 22 position the second wall 21 with a space between it and the first wall 20. However, if material, such as a bundle of wires, is wrapped which have excess circumference, the second wall 21 can expand to lie against the outer wall 20 due to the bending of the hinge portions 22, 22, without placing stress on the connection between the first and second walls. Yet, in normal position, a space between the walls 20 and 21 will be maintained due to the resilient stiffness of the hinge portions 22, 22 which position the second wall 21 inwardly of the first wall 20. The hinge portions extend laterally from the first and second planes of the first and second walls 20, 21, and can be at right angles thereto but are preferably slightly inclined to extend inwardly toward each other so that the length of the first wall 20 between the hinge portions is longer than the second wall. This permits the hinge portions to bend more easily, and to bend toward a position normal to the walls, when the strip is rolled into a tube with the second wall 21 on the inside.

The second wall 21 can be slit-lengthwise, at any suitable place along the entire length of the wall portion to create two flaps which may be used either to wrap two bundles of wire, each separately, or to use one of the flaps to cover the closure inside of the tube. This slitting would be along the dot dash line of FIGURE 3.

According to the method and apparatus aspects of the present invention, an extruder apparatus 25 is provided. Indicated at 26 is a discharge end of a heated extrusion cylinder, in which heated plastic material 27a is fed by a screw 28 through a discharge opening 29 into a chamber 30b of a head 31. Disposed in axial alignment with the propeller 28 in the chamber 30b is a molding structure or extruder portion 25a.

The molding structure 25a is preferably comprised of a series of three or more interchangeable blocks or forming die portions 26a, 26b, and 26c. Closure blocks or plates 26a and 26c comprise end blocks and have longitudinally or axially extending cavities or grooves therein indicated at 27 and 28 of predetermined configuration for extruding the closure strips or ends of the strip 10 indicated at 12 and 13 in FIGURE 2.

The central die portion 26b includes a main cavity or pocket area indicated generally at 29 and in which is mounted a separator wall structure or plate 30 which is suspended or hung within the pocket area 29 by means of a series of extensions 31 which extensions may comprise screws 31a extending through the block 26b into the separator 30 for vertical adjustment of the same within the pocket area 29 for varying the dimensions of the extruded product. In other words the screws 31a may be turned up or down to move the plate 30 up or down and thereby easily simultaneously change the thickness of both the first and second walls 20 and 21 of the tube. This readily controls the wall thickness for serving various purposes. As above described, the first wall 20 operates primarily to withstand the lateral stress imposed by the closure strip edges, and the second wall 21 acts as a second

spaced wall and as a cushioning member protecting the first wall and maintaining a space therebetween, with forces applied to the second wall being withstood by the second wall, and also by the hinge portions 22 at each end. When a special environment is presented which requires either more or less strength for lateral forces encountered by the first wall 20, or more or less strength for scuff resistance or insulating properties or similar requirements, the thicknesses of the walls can be readily changed. The present invention contemplates one form of structure wherein the walls are of the same thickness. The invention also contemplates a structure with a first wall 20 of a first thickness, and a second wall 21 of a heavier thickness to provide better insulative qualities and improved scuff resistance wherein either the inside or the outside of the tube is to be subjected to excessive scuff (the tube is then rolled with the wall 21 facing inwardly or outwardly as the situation may demand). The invention also contemplates a tube wherein the first wall 20 is of a first thickness which is larger than the thickness of the second wall 21, such as wherein the material must encounter substantial tensile stresses applied by forces circumferentially of the unit, but the wall 21 withstands little scuff and functions primarily to maintain an air space between the two walls, and to keep the material against the wall 21 away from the wall 20. The main pocket area 29 is defined at its periphery by a peripheral surface 29a (FIGURE 2) and the separator wall structure is defined at its periphery by a peripheral surface 30a whereby these surfaces 29a and 30a cooperate together to define superimposed wall cavities or grooves 32 and 33 with the wall portion 20 of the strip 10 or the tube 11 being formed within the cavity 32 and the wall portion 21 of the strip 10 or the tube 11 being formed within the wall cavity 33.

Transversely linking the cavities 32 and 33 are transverse link cavities or grooves indicated generally at 34, 34 wherein linking portions 22, 22 of the strip 10 or the tube 11 are formed during the extrusion process. It will be noted that the cavity 33 is in alignment with the fastener cavities or grooves 27 and 28 in the blocks 26a and 26c. In manufacturing a double wall strip one of the major problems faced was how to keep the walls apart after extrusion until they harden. To solve this problem, a fluid system has been developed.

To this end, a series of passageways 35 extend vertically downwardly through the block 26b and through the extensions 31 and then into the separator wall structure 30. A second series of passageways 36 extend through the separator block 30 which passageways are disposed at right angles to the passageways 35. A suitable fluid such as air is forced through the aligned passageways 35 and 36 from the top side of the block 26b through a supply conduit 37 and the fluid is discharged in a direction axially away from the screw 28 out through the openings or passageways 36 through the separator block 30 so that as the linked wall structure or strip 10 is discharged from the block 26b, the fluid will operate to maintain the superimposed walls 20 and 21 out of contact with one another until the walls are sufficiently solidified so that the wall structure will not collapse or become damaged upon discharge from the extruder portion 25a. The air passing through the passageways may be cooled such as by a cooler 38 to speed up hardening of the extruded plastic strip upon its discharge.

Recapitulating the process of my invention, the mass of heated plastic material is initially moved by the screw 28 into the chamber 30 thereby providing a large mass of plastic material which material is being moved axially against the molding or extruder portion 25a. The molding structure 25a operates to divide the mass of heated thermoplastic material into a series of wall streams and a series of linking streams by means of the cavity grooves 32, 33 and 34 while contemporaneously further molding and undulating the thermo-plastic material by means of the cavities or grooves 27 and 28 in the blocks 26a and

26b to provide fastener strips 12 and 13 at opposite ends of the wall portion 21.

As the same is passed through the molding structure 25a the relatively soft and pliable mass is formed to shape. The coolant which may comprise a cool air stream is directed through the passageways 35 and 36 preventing the soft pliable linked wall structure from collapsing until the heated thermo-plastic multi-walled strip-like mass is hardened and is formed into a form sustaining multi-wall strip 10 having fastener structure for forming the multi-wall strip into a tubular wall structure 11.

Through the use of the present method and apparatus the thickness of the web on which the ribs are mounted may at all times be kept to a minimum since there is no film or sheet to be welded to them as is the case with some of the conventional fasteners and a three piece tube may be in this manner avoided. Reducing the width of the web is of particular importance on tubes in reducing manufacturing cost, but further since when thin webs are used, the pliability of the tube becomes dependent upon the pliability of the wall as opposed to the pliability of the web where a thick web construction is used.

By utilizing a multi die-block construction, the die blocks can be used in a great many set ups without necessitating new die blocks and manufacturing costs may be thereby kept to a minimum.

It will be understood that modifications and variations may be effected without departing from the scope of the novel concepts of the present invention.

I claim as my invention:

1. A mechanism for extruding a multi-wall sheet having fastener elements at its edges and adapted to be rolled into a tube, the mechanism comprising means defining an extrusion chamber, a central die member having a die wall with an elongated die opening therein receiving extrudate from the chamber and provided with upper and lower edges defining outer wall surfaces of the sheet and side edges, edge die members beside the central die member having openings defining the outer surfaces of linking portions joined to the sheet formed by the central die member for joining the walls of the sheet, a plate member supported in said die opening of the central die member and constituting a mandrel having outer surfaces for defining the inner surfaces of the sheet walls, means for

adjustably supporting said plate member for adjusting its position relative to said opening of the central die member so that the thicknesses of said walls can be simultaneously changed, and means for forcing plastic material into said chamber and through the die openings.

2. A mechanism for extruding a multi-wall sheet having fastener elements at its edges and adapted to be rolled into a tube, the mechanism comprising means defining an extrusion chamber, a central die member having a die wall with an elongated die opening therein receiving extrudate from the chamber and provided with upper and lower edges defining outer wall surfaces of the sheet and side edges, edge die members beside the central die member having openings defining the outer surfaces of linking portions joined to the sheet formed by the central die member for joining the walls of the sheet, a plate member supported in said die opening of the central die member and constituting a mandrel having outer surfaces for defining the inner surfaces of the sheet walls, means for adjustably supporting said plate member for adjusting its position relative to said opening of the central die member so that the thicknesses of said walls can be simultaneously changed, means defining air emission openings in the edge of said plate member for directing a flow of air between the walls of the sheet, means for delivering air to said openings, and means for forcing plastic material into said chamber and through the die openings.
